UNITED STATES PATENT OFFICE

2,026,423

CONSTANT TEMPERATURE DEVICE

Marcus E. Fiene, Ballston Lake, N. Y., assignor to
General Electric Company, a corporation of
New York

Application September 27, 1933, Serial No. 691,262

22 Claims. (Cl. 236—1)

My invention relates to constant temperature devices, and it has for its object the provision of improved method and means for providing and holding predetermined constant temperatures.

This invention has general application, but it is particularly useful in those applications where it is imperative that the temperature be held at a predetermined fixed value, such as in radio frequency control systems wherein a piezo crystal is used.

I base my temperature control on the principle that the density of a saturated vapor is definitely correlated with the temperature; i. e., at a given density, a saturated vapor can have only one temperature. In order, therefore, to maintain a constant temperature, it is essential to maintain a constant density of the vapor and to keep it in the saturated condition.

I substantially effect the first requirement by confining a determined weight of a selected vaporizable fluid in a vessel or container of fixed volume and applying sufficient heat to vaporize substantially all of the free liquid. In order to maintain substantially all of the fluid at the saturation point, I apply heat to the fluid in such a manner that super-heating of the vapor within the vessel cannot occur. The amount of fluid that is introduced into the vessel is such that when all of the free liquid is vaporized the density of the vapor, and hence its temperature will have the desired value.

In order to vary the temperature, I change the density of the controlling vapor while holding it at the saturation point. In one form of my invention, I accomplish this by removing pre-selected quantities of the effective fluid from the container. In another form, I change the density of the vapor by varying its volume.

The vessel or container in one form of my invention is provided with a reentrant portion constituting a chamber which is used to receive the object whose temperature is to be controlled, such as the above-mentioned piezo crystal. A relatively long vapor tube communicates with the container through its bottom wall. This tube communicates with a vaporizer which is provided with suitable means for applying heat to it so as to vaporize the fluid within the vaporizer that exists in the liquid phase.

The control device, therefore, in brief consists in a vaporizer, a container which in effect functions somewhat as a condenser and a tube connecting the vaporizer with the container, all arranged into a closed system.

In one form of my invention, suitable means are provided for removing a portion of effective fluid from the closed system so as to vary the density of the vapor and hence, the temperature setting of the device. In another form of my invention, the density is varied so as to adjust the temperature setting by changing the volume of the container or condenser.

For a more complete understanding of my invention, reference should be had to the accompanying drawings, in which Fig. 1 is a vertical sectional view of a temperature control device embodying my invention; Fig. 2 is a vertical elevation illustrating a plurality of temperature control devices, each arranged as is the device shown in Fig. 1, and provided with common heating means for their vaporizers; Fig. 3 is a fragmentary sectional elevation illustrating the temperature control device shown in Fig. 1, but provided with means arranged in accordance with my invention for varying the density of the controlling fluid; Fig. 4 is a sectional elevation of a temperature control device illustrating means arranged in accordance with a modified form of my invention for varying the density of the controlling fluid; Fig. 5 is a fragmentary sectional elevation illustrating still different means for varying the density of the controlling fluid arranged in accordance with my invention; Fig. 6 is a fragmentary view of a portion of the device of Fig. 5; Fig. 7 is a sectional elevation of a modified form of my invention; and Fig. 8 is an elevation mainly in section of still a further modified form of my invention.

Referring more particularly to Fig. 1, I have shown my invention in one form as applied to a temperature control device comprising a container or condenser 10, a vaporizer 11 and a tube 12 connecting the vaporizer with the condenser into a closed fluid system of fixed volume. This tube 12, as shown, communicates with the condenser through its bottom wall 13. This wall preferably and as shown will have an inverted conical shape tapering downwardly to its center where it communicates with the tube 12. The vaporizer 11 should have a very small volume as compared with the volume of the closed system. Thus, it should preferably not be more than 0.1% of the total volume.

The chamber 14 for receiving the object (not shown) whose temperature is to be controlled is positioned within the condenser 10. This chamber, as shown, is arranged substantially centrally of the condenser and is supported from its upper wall 15. This wall 15 is provided with a cen-

trally arranged aperture 16 through which the chamber 14 is inserted into the condenser. The chamber 14 may be secured to the upper wall 15 in any suitable manner, as by brazing or welding.

- 5 Preferably, the bottom wall 14a of the chamber 14 will taper downwardly to its center, as clearly shown in Fig. 1. The purpose for this will be pointed out hereinafter in greater detail.

The article whose temperature is to be controlled is inserted into the chamber through its upper open end.

The outer walls of the container 10 and the vapor tube 12 preferably will be covered with a layer of insulating material 17. Any suitable insulating material may be used to form the layer 17, but I prefer to use mineral wool for this purpose. The insulating layer 17 covering the top wall 15 is provided with an aperture 17a through which access can be had to the chamber 14. This aperture will normally be covered by means of any suitable cover member (not shown).

Heat is applied to the vaporizer by means of a heating element 18, which as shown is formed into convolutions that surround the vaporizer. This heating element is provided with a suitable source of electrical supply 20. It will be understood that steam or any other suitable heating

agent may be used to heat the vaporizer 11. If desired, the heating element 18 may be controlled by means of a temperature responsive device 21 so as to avoid overheating. While any suitable temperature control device may be used, I prefer to use a control device of the type described and claimed in United States patent to A. H. Simmons, No. 1,743,073, dated January 7, 1930. Briefly, this temperature control device comprises a bi-metallic bar 22 which has one end fixed and its other end free to move in response to changes in temperature. This latter end bears on one arm of an inverted U-shaped spring 23, the other arm of which bears on a fixed pivot 24. The base of the spring carries a switch arm 25 which operates a switch 26 to open and close the energizing circuit for the heater 18. The temperature control device is arranged so that the bar 22 is in thermal relation with the heating element 18. As fully pointed out in the Simmons patent, when the temperature of the heating element, and hence of the vaporizer, reaches a predetermined maximum value, the bimetallic bar 22 will function to open the switch 26, where-as when the temperature of the heating element, that is of the vaporizer, reaches a predetermined low value, the bimetallic bar will close the switch 26 so as to reenergize the heating element. In this manner, the temperature control device functions to maintain a temperature in the vaporizer sufficiently above the temperature of the saturated vapor to keep all of the free liquid vaporized, and yet not so high as to cause injury to the vaporizer or heating element.

65 A quantity of a suitable vaporizable fluid, such as sulphur dioxide or difluor dichlor methane, or any other suitable fluid, is introduced into the container 10. This fluid may be passed into the container through a suitable tube 27 entering the chamber through its upper wall. It is preferable to substantially evacuate the container before the fluid is introduced. This may be accomplished by attaching a suitable vacuum apparatus to the tube 27. After the container has been evacuated and the selected fluid placed within it, the upper end of the tube 27 will be sealed.

The amount of fluid introduced into the system will be such that when all of the free liquid is

vaporized and maintained just at the saturation point, its density and hence, its temperature, will have the desired value; the selection of the fluid to be used, of course, depends upon the temperature-density characteristic of the fluid. 5 In other words, the choice of the fluid and the weight of the fluid used must be such that when all of the vapor has been evaporated and is maintained in a saturated condition, the fluid must have the density corresponding to the temperature at which it is desired to hold the controlled object. The choice of fluid also depends somewhat on the degree of temperature control desired. If very close control is required, a liquid is selected having a high vapor density at the 10 desired temperature because it has been found that in general a higher vapor density will give a closer temperature control. On the other hand, if very close temperature control is not required it may be advantageous to use a vapor having 15 a lower density, because usually low vapor pressures are associated with low vapor densities, and hence, the device can be designed for a lower operating pressure. 20

The fluid that is chosen, of course, must be one which will not attack the ordinary materials available for use for making the condenser, the vaporizer 11 and the vapor tube 12. 25

In the operation of the system, the object whose temperature is to be controlled is placed within the vessel 14 and the heating element 18 is energized. Initially some of the fluid will exist in the liquid phase, the free liquid collecting in the vaporizer 11. It will be understood that the free liquid is that portion of the fluid in the liquid phase which is free to flow to the vaporizer. When heat is applied to the vaporizer, a transfer of heat will take place between the vaporizer and the container 10 by evaporation in the vaporizer and by condensation in the chamber 10. 40

The heating element 18 functions to raise the temperature of the vaporizer to a value above that at which all of the free liquid will be vaporized. As heat is applied and the liquid in the vaporizer is vaporized, the temperature and pressure of the fluid within the chamber or condenser 10 increases until all of the free liquid in the vaporizer has been vaporized, when a condition of temperature equilibrium is reached. If a small mass of the vapor within the chamber 10 condenses because of loss of heat through the walls of the chamber, or for any other reason, it will flow back to the vaporizer where it will again be vaporized. The fluid thus vaporized will pass through the tube 12 to the condenser and in doing so will convey sufficient energy from the vaporizer to the condenser to maintain the condition of temperature equilibrium in the condenser. Actually there will be a constant transfer of heat from the vaporizer to the condenser in this manner. That is, fluid will constantly condense on the walls of the chambers 10 and 14 due to heat loss through the walls and will flow to the vaporizer through the tube 12. This liquid which gravitates to the vaporizer will be vaporized immediately and passed back to the chamber 18 as a saturated vapor. It is for this reason that the chambers 10 and 14 are provided with downwardly tapering bottom walls which function to direct the condensate directly to the tube 12.

In order to maintain the fluid within the condenser vaporized and yet at the same time prevent superheating of the vapor, I have thermally isolated the vaporizer 11 from the condenser in such a way that substantially no heat will pass

from the vaporizer to the condenser either by conduction or by convection, but can only pass by the flow of saturated vapor.

In order to accomplish this, I make the tube 12 of a metal having a relatively low thermal conductivity, such as steel or Monel metal. The tube 12 in addition to this has a relatively small cross-section so as to inhibit the transfer of heat from the vaporizer to the condenser by convection currents from the super-heated zone in the vaporizer. The diameter of the tube should preferably be 8 mm. or less. It has been found that if the diameter is this small there will be no transfer of heat by convection of the superheated vapor from the vaporizer to the condenser. By reason of the foregoing construction, and because vaporized fluid itself is a poor conductor of heat, the vapor in the condenser 18 cannot possibly become superheated.

This arrangement of the vapor tube imposes a limitation on the maximum rate of flow of the saturated vapor from the vaporizer to the condenser. Because of this, if a relatively large condenser is used it is preferable to use a plurality of vapor tubes connecting the condenser with the vaporizer.

Actually, it has been found that the expansion of vapor within the vaporizer due to the superheat will increase somewhat the density of the vapor in the condenser, but this increase will be very slight because of the fact that the volume of this super-heated vapor in the vaporizer is only about 0.1% of the total volume. Actual tests have demonstrated that the temperature of the vapor in the condensing chamber varies only about 0.001° per degree of variation in the temperature of the vapor in the vaporizer.

Because of this, it is not essential that the heating element 18 be controlled to maintain a substantially constant temperature in the vaporizer. Variations in the wattage input will vary the superheat in the condenser, but this variation, as previously pointed out, has practically no effect on the condenser temperature, that is, the temperature in the vessel 14. In other words, my device can utilize the heat generated at a source of varying temperature and make this heat available at a constant temperature.

It will be observed that my control device of Fig. 1 functions to vaporize virtually all of a fixed weight of a vaporizable fluid which is within a container of substantially constant volume and maintains the fluid in the saturated condition. Thus, it maintains at a definite value the density of a saturated vapor. As is well understood under such conditions, the temperature of the fluid in the condenser will be held at a substantially constant value and hence, the object or device within the chamber 14 will be held at a substantially constant temperature.

As previously pointed out, not quite all of the fluid will be in the vapor phase when the system has reached an equilibrium temperature. Heat leakage through the insulation layer 17 will cause a slow condensation on the container walls and because of this there will be a substantially constant flow of liquid into the vaporizer 11 where it will be vaporized immediately. Changes in the ambient temperature will change the rate of liquid condensation and return to the vaporizer and hence will affect the amount of fluid existing in the liquid phase but it has been found that this effect is so small that it will not affect the temperature appreciably. Thus, with the control device shown in Fig. 1 where the condenser

has a height of approximately 10 inches and a diameter of approximately 9 inches, and where sulphur dioxide is used as the controlling fluid, it has been found that this does not cause a variation in the temperature of the condenser chamber of more than 0.01° per degree variation in the ambient temperature. This variation can be reduced by increasing the volume of the condenser.

It is to be noted, of course, that my device will not function if the ambient temperature is higher than the temperature desired in the chamber 14, nor will it function when the vaporizer temperature is below the temperature desired in the chamber 14.

It will be understood that while the vapor tube 12 will be formed of a material having a relatively low heat conductivity, it is preferable to form the vaporizer 11 of a material having a relatively good conductivity, such as copper. The copper vaporizer 11 may be secured to the vapor tube 12 in any suitable manner, as by welding or brazing.

In Fig. 2 I have illustrated a plurality of control devices arranged in identically the same fashion as the temperature control device of Fig. 1, but provided with a common heating unit for their vaporizers. As shown in this figure, a pair of temperature control devices 30 and 31 are provided with vaporizers 32 and 33 respectively. The vaporizers 32 and 33 are arranged in a position relatively close to each other and are surrounded by convolutions of a suitable heating element 34 which, as shown, is arranged to apply heat to both of the vaporizers at the same time. The heating element 34 is energized from a suitable electrical supply source 35. The energization of the heating element is controlled by means of a suitable temperature control device 36 which may have any suitable form, but which preferably will be constructed as is the temperature control device 21 of Fig. 1.

The advantage of this arrangement is that substantially constant temperatures of widely different values can be maintained at the same time in the two control devices 30 and 31 by means of only one heating element. For example, it might be desirable to design a cabinet having two compartments held at different temperatures for use of pathological laboratories. For such applications, the temperatures for example may be 37.5° C. and 55° C. This arrangement, therefore, is quite economical in its operation. It will be understood, of course, that the controlling fluids which will provide widely different temperatures can be used in the two control devices.

Moreover, it will be understood that three or four more control devices may be arranged to be controlled by a single heating element, as shown in Fig. 2.

In Fig. 3, I have shown means for varying the density and hence the temperature held by the control device by changing the volume of the condenser. As shown in Fig. 3, the condenser 40 encloses a chamber 41 in which the object whose temperature is to be controlled is placed. The condenser 40 and the chamber 41 are arranged in substantially the same fashion as are the condenser 10 and chamber 14 of Fig. 1. Moreover, it will be understood that the condenser 40 communicates with a vaporizer by means of a fluid tube all arranged in substantially the same fashion as are the corresponding elements of Fig. 1.

A bellows or accordion-like member 42 is mounted in an aperture 43 provided for it in the

side wall of the condenser so as to project into the condenser. The side walls and inner end of the bellows are completely closed, that is, they are impervious to leakage of fluids, and the inner end is mounted in the aperture with a fluid-tight joint between the bellows and the condenser. The bellows may be expanded and contracted by means of an adjusting rod 44 connected at its inner end to the inner end wall of the bellows and passed through the bellows to the exterior of the condenser, as shown in Fig. 3. The adjusting rod is threaded at its outer end and on this threaded portion is received an adjusting knob 45. The knob is restrained from longitudinal movement on the rod 44 by means of a plate 46 which functions to support the knob 45 and which, as shown, is provided with an aperture 47 which is received in a peripheral groove or recess 48 provided in the knob.

It will be obvious that by turning the knob 45, the position of the rod 44 and hence the position of the bellows can be changed. To expand the bellows it is merely necessary to turn the knob 45 so as to move the rod 44 inwardly of the condenser, whilst to contract the bellows it is merely necessary to turn the knob 45 in the opposite direction so as to retract the rod 44.

In other words, the effective volume of the controlling fluid within the closed system can be adjusted merely by turning the knob 45. Of course, the density of the fluid is changed when the volume of the chamber 40 is varied. If the volume is increased by contracting the bellows, the density will be decreased. On the other hand, if the volume is reduced by expanding the bellows, the density will be increased. As is well understood by those skilled in the art, when the density of a saturated vapor is changed, the equilibrium temperature of the vapor will change with it. More specifically, the equilibrium temperature increases with increase in the density, and decreases when the density is decreased. In this manner the temperature held by the control device can be controlled merely by turning the knob 45.

I have shown in Fig. 4 a modified form of my invention wherein a different means is provided for adjusting the density of the fluid, and hence the temperature setting of the control device. In the form shown in Fig. 4 I effect this adjustment by rendering a portion of the fluid ineffective.

The temperature control device shown in Fig. 4 comprises a condenser 50, a vaporizer 51, and a vapor tube 52 connecting the condenser and the vaporizer in to a closed system. These members are arranged in substantially the same fashion as are the corresponding elements shown in Fig. 1. The condenser 50 receives a chamber 53 similar to the chamber 14 of Fig. 1. The vaporizer 51 is heated by means of an electrical heating element 54 which is energized from a suitable source of electrical supply 55 and is controlled by a temperature control device 56.

The bottom wall 57 of the condenser 50, however, is not of conical form, as is the bottom wall 13 of Fig. 1. On the contrary, the bottom wall 57 is formed as a plane surface. And the tube 52 of Fig. 4, rather than communicating with the condenser 50 through the central portion of the bottom wall communicates with it at a point relatively close to a side wall of the condenser, as clearly shown in Fig. 4.

In this arrangement of Fig. 4, it is contemplated that the condenser 50 will be supported in a position inclined to the vertical, rather than

in a vertical position, as is the condenser 10 of Fig. 1. It is also contemplated that the condenser will be supported by means of some suitable means whereby its position can be adjusted. For this purpose, the condenser 50 is supported in a clamping collar 59 surrounding the condenser 50. It is preferable to interpose a suitable metallic bushing 60 between the collar 59 and the insulating layer 61 that covers the condenser. The collar 59 is carried by means of a rigid supporting frame 62. The condenser 50 may be rotated in the collar 59 about its longitudinal axis to any suitable position where it will be locked or secured by the ring.

In the operation of this form of the invention, 15 it will be observed that when the heater 54 is energized it will vaporize substantially all of the liquid in the system, with the exception of that which is trapped in a pool 63 in the lower corner of the condenser. The level of this pool is determined by the position of the mouth of the tube 52. In other words, liquid can collect in this pool until the liquid level rises to the mouth of the tube 52, whereupon any more liquid flowing to the pool will overflow into the tube 52 and thence to the vaporizer.

It will be obvious that the quantity of liquid that will collect in the pool 63 before it overflows to the tube 52 will depend upon the position of the condenser 50. If the condenser 50 be rotated 30 so as to raise the position of the mouth of the tube 52, more liquid will be allowed to collect in the pool 63.

In this manner, the weight of effective fluid within the closed system can be controlled so 35 as to control the density of the vapor and hence, the equilibrium temperature that is held within the chamber 53. If the effective weight of the fluid be reduced by increasing the volume of the liquid pool 63, the density of the vapor will be reduced, and as a result, the temperature maintained in the chamber 53 will be reduced. On the other hand, if the weight of the effective fluid within the system be increased by decreasing the size of the liquid pool 63, the density will be increased and a higher temperature will be held in the chamber 53.

The weight of effective fluid can be controlled over a relatively wide range of values, and as a result, the temperature setting of the device can 50 be controlled over a relatively wide temperature range. As a matter of fact, by suitably varying the weight of the effective fluid, the temperature can be adjusted through a range having substantially the ambient temperature as the lower limit 55 and the critical temperature of the fluid as the upper limit.

In Fig. 5, I have shown apparatus of modified form for changing the effective weight of fluid within the system. In Fig. 5, the condenser 66 is of substantially the same form as is the condenser 10 of Fig. 1. Thus, it is provided with a bottom wall 66 that has the shape of an inverted cone. In the center of this bottom wall is an aperture 66a which communicates with a vapor tube 67 which in turn communicates with a vaporizer 68. The vaporizer 68 is heated by means of a suitable heating element 70. The vapor which is generated by evaporation of liquid in the vaporizer 68 instead of being directed back 70 into the condenser through the pipe 67 is conducted to the condenser through a separate return pipe 71 which, as shown in Fig. 5, communicates with the condenser through its side wall at a point adjacent the bottom wall 66. It will be

understood, however, that the vapor tube may be similar to that shown in Fig. 1.

The pipe 67, as shown, does not enter the condenser but enters a separate somewhat larger conduit 72 which in turn communicates with the condenser through the aperture 66a. The fluid conduit 67, as shown, projects upwardly into the conduit 72 for some distance. This arrangement provides an annular space 73 between the two conduits 67 and 72. This annular space functions to collect condensate gravitating from the condenser 65.

The annular space 73 communicates with an annular chamber 74 surrounding the conduit 72 through a flexible conduit member 75. This member 75, as shown, has one end connected to the lower end of the annular passageway 73 and its other end connected with the bottom of the annular chamber 74.

It will be observed that by reason of this arrangement the condensate which collects in the chamber 73 can flow directly into the chamber 74 and that the liquid levels in the two chambers 73 and 74 will be the same. The maximum level is determined, of course, by the height of the tube 67 above the bottom of the annular chamber 73.

The quantity of liquid that is allowed to collect in the chambers 73 and 74 is controlled by adjusting the vertical position of the chamber 74. This chamber, as shown, is supported for vertical movement upon a plurality of rods 76 which depend from the bottom of the wall 66. The position of the chamber 74 is adjusted by means of a screw 71 passing through the bottom wall of an insulating covering 78 provided for the control apparatus, as clearly shown in Fig. 5. Preferably, a suitable bushing 79 will be arranged in this insulating wall for receiving the screw. It will be understood that by turning the screw to move it upwardly the chamber 74 will be moved upwardly, which of course will cause liquid in the chambers 73 and 74 to overflow into the conduit 67 from which it finds its way to the evaporator 68. If the screw be turned so as to permit the annular chamber 74 to move downwardly, more of the condensate will be allowed to collect in the chamber before it will overflow. In this manner, the weight of working fluid within the system is controlled.

The upper end of the chamber 74 will be vented by means of a flexible conduit 80 which places the upper portion of the chamber in communication with the condenser 65 as clearly shown in Fig. 5.

The vertical axes of the tube 67 and the annular chamber 74 preferably should be made to coincide, and preferably the tube 67 should be arranged so that liquid will flow into it from the annular chamber 73 along the vertical axis of the tube. To accomplish this the tube 67 at its upper end is bent inwardly so that a portion 81 of the wall will be in this axis. Within this portion a V-shaped notch 81a is formed so that the bottom of the V lies in the axis of the tube.

This arrangement is important because it insures a practically constant volume of trapped liquid in the chambers 73 and 74 regardless of change of position of the device away from the vertical, within limits.

As previously pointed out, the temperature maintained by my control device will vary slightly with changes in the ambient temperature. Moreover, as previously pointed out, the temperature will also vary somewhat with variations in the super-heat temperature in the vaporizer.

However, it may be that in some applications a more sensitive control is desired. In Fig. 7, I have shown a form of my invention which will provide a more sensitive control. In Fig. 7 this is accomplished by enveloping the condenser for the primary controlling fluid with an atmosphere constituting a secondary controlling fluid, the temperature of which is held substantially constant in accordance with my invention. In this arrangement, it will be observed that while the temperature of the secondary fluid will change to a small degree with changes in the ambient temperature, the temperature variation of the primary controlling fluid resulting from changes in the ambient temperature will be practically negligible.

Moreover, in this form of the invention, the condensers for the primary and secondary fluids are maintained at a substantially constant temperature by means of a control device arranged in accordance with my invention.

Referring more particularly to Fig. 7, the condenser 90 for the primary controlling fluid is connected with a vaporizer 91 by means of a tubular member 92. A chamber 93 is provided to receive the object whose temperature is to be controlled. The members 90, 91, 92, and 93 are arranged and operate in substantially the same fashion as the corresponding elements of Fig. 1.

Surrounding the condenser 90 is a second condenser 94 for receiving the secondary controlling fluid. The condenser 94 is arranged so that the secondary fluid substantially completely envelopes the primary condenser 90. The condenser 94 is connected with a vaporizer 95 by means of a tubular member 96. The members 94, 95, and 96 are arranged and operate in substantially the same fashion as the corresponding elements shown in Fig. 1.

Preferably the tubes 92 and 96 will be provided with bends 92a and 96a respectively which assist in preventing the transfer of heat by convection currents from the vaporizers to the condensers.

Preferably, the outer walls of the condensers 90 and 94 and of the tubular members 92 and 96 will be covered with a suitable heat insulating material 97. It is also preferable to completely fill the space between the evaporators with the insulating material.

A common source of heat is provided for the vaporizers 91 and 95. This source is controlled to hold a substantially constant temperature by a control device 98 arranged in accordance with my invention. This control device, as shown, comprises a condenser 100 which is connected with a vaporizer 101 by means of a tubular member 102. The vaporizer 101 is heated by a suitable heating element 103 which is energized from a source of supply 104. The vaporizer and tubular member 102 are thermally insulated by a layer 105 of a suitable insulating material.

As shown, the vaporizers 91 and 95 are received in the condenser 100. They are preferably inserted into the chamber through the upper wall of the condenser. Of course, fluid-tight seals will be provided between the tubes 92 and 96 and the upper wall of the condenser.

In the operation of this form of my invention, it will be understood that the temperature control device 98 functions to hold a substantially constant temperature in the vaporizers 91 and 95. The temperature of the super-heated vapor in the vaporizers 91 and 95, therefore will be practically unaffected by changes in the ambient temperature, and by variations in the tempera- 75

ture of the super-heated vapor in the vaporizer 101. This, of course, results in an extremely small temperature variation in the primary and secondary fluids in the condenser chambers 90 and 94 due to temperature variation in the super-heat in the vaporizer 101.

It is necessary that the temperature in the secondary controlling fluid be somewhat lower than the temperature of the primary controlling fluid. 10 It is also necessary that the temperature of the controlling fluid in the condenser chamber 100 be somewhat higher than the temperatures of the controlling fluids in the chambers 90 and 94. Thus, if the desired temperature in the chamber 93 is 65° C., the temperature held by the secondary fluid may be 50° C., while the control device 98 will maintain say 120° C. in the evaporators 91 and 95.

In Fig. 8 I have shown a modified form of my 20 invention which is in the main quite similar in construction to the form shown in Fig. 5, but it has additional means for compensating for change in ambient temperature. This compensation is 25 accomplished by varying the weight of the effective fluid in the system in accordance with variations in the ambient temperature.

As shown in Fig. 8, this control device comprises a condenser 106, a vaporizer 107 connected into a closed fluid system with the condenser 106 30 by means of a vapor tube 108. The tube 108 functions both to convey the condensate to the vaporizer and to return the vaporized fluid to the condenser. In other words, the return conduit 11 of Fig. 5 has been eliminated. The tube 108 35 is similar to the tubes 92, 96 and 102 of Fig. 7.

The tube 108 is connected to the condenser by a tubular member 110, the parts being arranged to define an annular liquid trap 111. The trap 111 communicates with an annular chamber 112 40 surrounding the tube 110 by means of a flexible tube 113. The upper portion of the chamber 112 is vented by means of a flexible tubular member 114 which connects this portion of the annular chamber with the condenser chamber 106, as 45 shown in Fig. 5.

All of these parts including the tube 108, the tubular member 110, the chamber 112 and the conduits 113 and 114 are arranged in substantially the same fashion as are the corresponding 50 elements shown in Fig. 5.

The position of the chamber 112 is controlled by means of a suitable adjusting screw 115.

Additional means are provided for controlling the position of the chamber 112 in accordance 55 with the changes in the ambient temperature. This additional means comprises a reservoir or bulb 116 on the exterior of the insulating wall 117 provided for the control device so that it is subject directly to changes in the ambient temperature. The reservoir 116 communicates with an expansible bellows, or accordion-like member 118 which is arranged to adjust the position of the chamber 112. The bulb or reservoir 116 and the bellows 118 are filled with a fluid which has 60 a relatively high temperature coefficient of expansion, such as turpentine.

The adjusting screw 115, as shown, is directly connected to move a platform or plate 120. This plate is mechanically connected to a second plate 70 121 by means of the bellows 118. The plate 121 in turn is connected with the chamber 112 by means of columns 122. These columns 122 are arranged to slide vertically on rods 123 depending from the lower wall of the condenser chamber 75 108.

It is to be understood that the bellows 118 is sufficiently rigid to prevent relative movement between the plates 120 and 121 except when the bellows is operated in response to a change in the ambient temperature. Thus, when the screw 5 115 is adjusted it will impart motion to the chamber 112 through the plates 120 and 121, the bellows 118 and the columns 122, all connected as a rigid system.

Once the screw 115 has been adjusted, however, the plate 120 from then on remains as a fixed member. If any change occurs in the ambient temperature, the liquid in the bulb 116 will expand or contract, depending upon whether the temperature rises or falls, and will expand the 15 bellows or allow it to contract, as the case may be. One end of the bellows is fixed or anchored to the fixed plate 120, while its other end is free to move the plate 121, and hence the member 112.

In the operation of this form of the invention, 20 the screw 115 will be adjusted so as to adjust the temperature setting of the control device to hold a predetermined constant temperature. If then the ambient temperature increases, the amount of liquid in the condensate film on the walls of 25 the condenser 106 obviously will be decreased. When the ambient temperature thus increases, the liquid in the bulb 116 will expand and the bellows will be extended so as to lower the chamber 112. This operation will allow more of the 30 liquid to be trapped in the chamber 112. The expansion of the liquid in the bulb 116 controls the bellows 118 to lower the chamber 112 sufficiently to increase the amount of condensate collected so as to compensate for the reduced amount 35 of liquid in the condensate film.

Conversely, if the ambient temperature decreases, the liquid in the bulb causes the bellows to contract so as to elevate the chamber 112 and thereby reduce the amount of condensate that is 40 removed from the system so as to compensate for the increased amount of liquid in the condensate film resulting from reduced ambient temperature.

In this manner, the bulb 116 functions to keep 45 the density of the vapor substantially constant and thereby maintain the temperature constant in the condenser chamber.

While I have shown particular embodiments 50 of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. A temperature control device comprising a closed chamber constituting a condenser, a vaporizer remote from said condenser, a conduit 60 connecting said vaporizer with said chamber arranged to prevent the transfer of heat by conduction and convection between said vaporizer and said chamber, a vaporizable fluid within said vaporizer and condenser and means for heating 65 said vaporizer to a temperature sufficiently high to vaporize substantially all of said fluid in said vaporizer that exists in the liquid phase.

2. A temperature control device comprising a closed chamber constituting a condenser, a vaporizer in fluid communication with said condenser, a vaporizable fluid within said condenser and vaporizer, means for applying heat to said vaporizer to vaporize the fluid in said vaporizer that is in the liquid phase and means inhibiting 70 75

the transfer of heat by conduction and convection from said vaporizer to said condenser.

3. A temperature control device comprising a closed chamber constituting a condenser, a vaporizer, a vaporizable fluid within said condenser, a conduit between said condenser and said vaporizer having a relatively poor heat conductivity and arranged so as to prevent a material transfer of heat between said vaporizer and said condenser by convection in the fluid in said conduit and means for heating said vaporizer.

4. A temperature control device comprising a chamber for receiving a charge whose temperature is to be controlled, a closed chamber surrounding a material portion of said first chamber, a vaporizer remotely situated with respect to said chamber, a conduit between said vaporizer and said second chamber connecting said vaporizer and chamber into a closed system, a selected vaporizable fluid in said closed system and means for heating said vaporizer to a temperature sufficiently high to vaporize substantially all of the fluid in said vaporizer that exists in the liquid phase, said conduit having a cross-sectional area sufficiently small to inhibit convection currents in the vaporized fluid in said conduit.

5. In combination, a closed chamber constituting a condenser, a vaporizer, a tubular member connecting said condenser and vaporizer into a closed system arranged so that any liquid in said system will gravitate to said vaporizer, a fixed weight of a vaporizable fluid in said system and means for applying heat to said vaporizer so as to vaporize any of said fluid that exists in the liquid phase, said tubular member being arranged to substantially inhibit the conduction of heat between said vaporizer and said condenser and having a cross-sectional area sufficiently small to inhibit the transfer of heat by convection between said vaporizer and said condenser.

6. A temperature control device comprising a closed condenser chamber, a vaporizable fluid in said chamber, a vaporizer, a conduit connecting said vaporizer with said chamber arranged to prevent the transfer of heat by conduction and convection between said vaporizer and said chamber, means for applying heat to said vaporizer so as to vaporize substantially all of the free liquid in said vaporizer, and means for controlling the density of the vapor in said condenser chamber.

7. A temperature control device comprising a closed condenser chamber, a vaporizer, a conduit connecting said vaporizer with said chamber arranged to prevent the transfer of heat by conduction and convection between said vaporizer and said chamber, means for applying heat to said vaporizer so as to vaporize substantially all of the free liquid in said vaporizer and means for changing the volume of said condenser chamber.

8. A temperature control device comprising a closed chamber constituting a condenser, a vaporizer in fluid communication with said condenser, a vaporizable fluid within said condenser and vaporizer, means for applying heat to said vaporizer to vaporize substantially all of the fluid in said vaporizer that exists in the liquid phase, means for inhibiting the transfer of heat by conduction and convection from said vaporizer to said condenser so that the temperature in said condenser is held at a substantially constant selected value and a collapsible wall portion in said condenser arranged to be expanded and contracted so as to vary the effective volume of

said condenser and thereby the temperature setting of said device.

9. A temperature control device comprising a condenser and a vaporizer connected in a closed system arranged so that fluid existing in the liquid phase in said system gravitates to said vaporizer, a selected vaporizable fluid in said closed system, means for applying heat to said vaporizer so as to vaporize substantially all of the fluid in said vaporizer that exists in the liquid phase, means substantially inhibiting the transfer of heat by conduction and convection from said vaporizer to said condenser and means for varying the weight of effective fluid in the vapor phase of said closed system.

10. A temperature control device comprising a condenser chamber, a vaporizable fluid in said chamber, a vaporizer, a tubular member connecting said condenser and vaporizer into a closed fluid system arranged so that the fluid in said system existing in the liquid phase gravitates to said vaporizer, said tubular member having a very poor heat conductivity and being arranged so as to inhibit convection currents in the vapor existing in said tubular member, means for heating said vaporizer sufficiently to vaporize substantially all of the fluid in said vaporizer that exists in the liquid phase and liquid collecting means for intercepting pre-selected quantities of the fluid that condenses in said condenser and gravitates to said vaporizer in the liquid phase so as to vary the weight of effective fluid in the vapor phase in said closed system.

11. A temperature control device comprising a condenser and a vaporizer connected in a closed fluid system, a selected vaporizable fluid in said closed system, means for applying heat to said vaporizer to vaporize the fluid therein existing in the liquid phase, a fluid envelope for said condenser, and means controlling the temperature of said envelope.

12. A temperature control device comprising a condenser and a vaporizer connected in a closed fluid system, a selected vaporizable fluid in said closed system, means for applying heat to said vaporizer to vaporize the fluid therein existing in the liquid phase, a second condenser surrounding said first condenser connected with a vaporizer in a closed fluid system, a selected vaporizable fluid in said second condenser and means for applying heat to said second vaporizer to vaporize the fluid therein existing in the liquid phase.

13. A temperature control device comprising a condenser and a vaporizer connected in a closed fluid system, a selected vaporizable fluid in said closed system, means for applying heat to said vaporizer to vaporize the fluid therein existing in the liquid phase, and means controlling the density of the fluid in said system in accordance with the ambient temperature.

14. A temperature control device comprising a condenser and a vaporizer connected in a closed system arranged so that fluid existing in the liquid phase in said system gravitates to said vaporizer, a selected vaporizable fluid in said closed system, means for applying heat to said vaporizer so as to vaporize substantially all of the fluid in said vaporizer that exists in the liquid phase and means responsive to the ambient temperature for varying the weight of effective fluid in said closed system so as to control the density of the vapor in said system.

15. A temperature control device comprising

5 a condensing chamber, a vaporizer in fluid communication with said condensing chamber, heating means for applying heat to said vaporizer to vaporize the fluid in said vaporizer that is in the liquid phase, means inhibiting the transfer of heat by conduction and convection from said vaporizer to said condenser, and means responsive to the temperature of said heating means controlling said heating means to hold a substantially mean temperature between predetermined maximum and minimum temperatures.

10 16. A temperature control device comprising a condenser and a vaporizer connected in a closed system arranged so that fluid existing in the liquid phase in said system gravitates to said vaporizer, means for applying heat to said vaporizer so as to vaporize substantially all of the fluid in said vaporizer that exists in the liquid phase, a fluid collecting chamber arranged to intercept liquid gravitating to said vaporizer, a second chamber in fluid communication with said collecting chamber and arranged to be adjusted relative to said collecting chamber so as to vary the quantity of fluid in said collecting chamber, and means for adjusting said second chamber.

15 17. A temperature control device comprising a condenser and a vaporizer connected in a closed system arranged so that fluid existing in the liquid phase in said system gravitates to said vaporizer, means for applying heat to said vaporizer so as to vaporize substantially all of the fluid in said vaporizer that exists in the liquid phase, a liquid collecting chamber arranged to intercept liquid gravitating to said vaporizer, a second chamber in fluid communication with said collecting chamber and arranged to be adjusted relative to said collecting chamber so as to vary the quantity of fluid in said collecting chamber, and means responsive to the ambient temperature controlling the position of said second chamber.

20 18. A temperature control device comprising a condenser chamber, a vaporizable fluid in said chamber, a vaporizer, a tubular member connecting said condenser and vaporizer into a closed fluid system arranged so that the fluid in said system existing in the liquid phase gravitates to said vaporizer, and walls defining an annular chamber surrounding the upper end of said tube

25 with the axis of said chamber substantially co-axial with the axis of said tube and arranged to collect fluid gravitating to said vaporizer, the upper end of said tube constituting an over-flow for said annular chamber and arranged so that fluid flows into said tube from said chamber substantially along the axis of said tube.

19. The method of controlling the temperature of a charge which comprises heating a predetermined volume and weight of a vaporizable fluid 10 sufficiently to vaporize substantially all of the fluid that exists in liquid phase but without super-heating the vapor, and thereby effect an equilibrium temperature in said vapor, and bringing said charge into thermal relation with said 15 vapor.

20. The method of controlling the temperature of a charge which comprises heating a predetermined weight and volume of a vaporizable fluid to vaporize substantially all of the fluid in said 20 system that exists in the liquid phase, but without super-heating the vapor to thereby effect an equilibrium temperature, bringing said charge into thermal relation with the vaporized fluid, and varying the density of said vapor so as to 25 vary said equilibrium temperature.

21. The method of controlling the temperature of a charge which consists in heating a predetermined weight and volume of a vaporizable fluid to vaporize substantially all of the 30 fluid existing in the liquid phase, but without super-heating the vapor, thereby effecting an equilibrium temperature, bringing said charge into thermal relation with said vapor, and varying the volume of said vapor so as to vary the 35 equilibrium temperature.

22. The method of controlling the temperature of a charge which consists in heating a predetermined weight and volume of a vaporizable 40 fluid sufficiently to vaporize substantially all of said fluid existing in the liquid phase, but without super-heating the vapor, thereby effecting an equilibrium temperature, bringing said charge into thermal relation with said vapor, and varying the effective weight of said vapor at constant volume so as to vary said equilibrium temperature.

MARCUS E. FIENE.
